UNITED STATES PATENT OFFICE.

JOSEPH E. BROWN AND HENRY H. WINTERS, OF VICTORIA, KANSAS.

GRAIN-DOOR.

SPECIFICATION forming part of Letters Patent No. 664,621, dated December 25, 1900.

Application filed June 27, 1900. Serial No. 21,741. (No model.)

To all whom it may concern:

Be it known that we, JOSEPH E. BROWN and HENRY H. WINTERS, citizens of the United States, and residents of Victoria, in the county 5 of Ellis and State of Kansas, have invented a new and Improved Grain-Door, of which the following is a full, clear, and exact description.

This invention relates to a door for box 10 freight-cars, and especially one adapted to carry grain, the door being constructed to prevent the leakage of the grain from the car.

This specification is the disclosure of one 15 form of the invention, while the claims define the actual scope thereof.

Reference is to be had to the accompanying drawings, forming a part of this specification, in which similar characters of reference indicate corresponding parts in all the 20 views.

Figure 1 is an interior side elevation of the device. Fig. 2 is a section on the line 2 2 of Fig. 1. Fig. 3 is a horizontal section on the line 3 3 of Fig. 1, and Fig. 4 is a detail perspective view of the cleat which secures one 25 edge of the door.

a represents the car-body, which has the door-opening *a'*. The door *b* may be of any height desired, or it may be made in a plural 30 ity of sections, if preferred. At one side of the door-opening a cleat *c* is rigidly fastened to the car, the cleat having an overhanging portion or ledge *c'* projecting toward the door-opening and spaced from the side of the car. 35 The inner face of this ledge is formed with transverse ribs *c*, adapted to have the door *b* driven against them, the side of the door being wedged between the ledge and the car, and the working face of this ledge *c'* is inclined, 40 so as to facilitate the wedging of the door in place, as illustrated best in Fig. 3. At the opposite side of the door-opening *a'* the car is provided with a bar *d*, the lower end of which is turned laterally to form a foot which 45 is held to slide transversely of the car in a keeper *e*, and the upper end of which bar *d* is free, the bar being arranged to be forced against the side of the car by means of a nut

d' working on a screw *d*, fastened rigidly to the car. The inner face of the bar *d* is formed 50 with projections *d*, adapted to engage with the door *b*, the door being inserted between the bar *d* and the inner side wall of the car. The door-jamb is formed with a vertical groove *a*, before which the bar *d* lies when working 55 with the door *b*; but when the door is removed and the car used for freight other than grain the bar *d* is moved up into the groove *a*, so as to lie flush with the inner side of the car.

In the use of the invention the door *b* is 60 placed with its lower edge on the floor of the car, and one side of the door is driven between the ledge *c'* and the side of the car. The thumb-nut *d* is then tightened to draw the bar *d* against one side of the door, thus 65 firmly and rigidly holding the door in place. When it is desired to open the door, the bar *d* may be released and the door may then be readily disengaged from the ledge *c'*.

This invention does not hinder in any way 70 the use of the car for purposes other than carrying grain, since the parts *c* and *d* occupy very little space and are not in the way of the load in the car.

Having thus described our invention, we 75 claim as new and desire to secure by Letters Patent—

1. A railway-car grain-door fastening, comprising a cleat with an overhanging portion or ledge, the inner face of which is formed 80 with transverse ribs adapted to be engaged by the grain-door to hold one end in place, the cleat being fastened rigidly to the railway-car at one side of the door-opening, a bar arranged at the other side of the door-opening 85 and having its lower end turned laterally to form a foot, a keeper fastened on the floor of the car loosely to receive the foot of the bar, and means at the upper end of the bar for drawing the same toward the car-body, to 90 clamp the grain-door between the bar and the car.

2. A railway-car grain-door fastening, comprising means at one side of the door-opening for holding one end of the grain-door, a bar 95 at the other side of the door-opening, the bar

being disposed vertically and having its lower end turned horizontally to form a foot, a keeper on the floor of the car, in which keeper the foot is loosely mounted, and means at the 5 upper end of the bar for drawing the bar toward the car-body to clamp the grain-door between the bar and the car.

In testimony whereof we have signed our

names to this specification in the presence of two subscribing witnesses.

JOSEPH E. BROWN.
HENRY H. WINTERS.
